(57) **CLAIM**

The ornamental design for a portable electric hammer body as shown and described.

DESCRIPTION

FIG. 1 is a front, left, and top perspective view of a portable electric hammer body in accordance with our new design; FIG. 2 is a rear, right, and bottom perspective view of the portable electric hammer body in accordance with our new design;

FIG. 3 is a front elevational view of the portable electric hammer body in accordance with our new design;

FIG. 4 is a rear elevational view of the portable electric hammer body in accordance with our new design;

FIG. 5 is a top plan view of the portable electric hammer body in accordance with our new design;

FIG. 6 is a bottom plan view of the portable electric hammer body in accordance with our new design;

FIG. 7 is a right side elevational view of the portable electric hammer body in accordance with our new design; and, FIG. 8 is a left side elevational view of the portable electric hammer body in accordance with our new design.

The broken lines in the drawings illustrate portions of the portable electric hammer body which form no part of the claimed design.

1 Claim, 8 Drawing Sheets
